UNITED STATES PATENT OFFICE.

WILLIAM JOHN KNOX, OF NEW YORK, N. Y., ASSIGNOR TO KNOX TERPEZONE COMPANY OF AMERICA, A CORPORATION OF WEST VIRGINIA.

APPARATUS FOR GENERATING OZONE.

1,130,827.

Specification of Letters Patent.

Patented Mar. 9, 1915.

Application filed December 1, 1910. Serial No. 595,014.

To all whom it may concern:

Be it known that I, WILLIAM JOHN KNOX, a citizen of the United States, and a resident of the borough of Manhattan, in the city of New York, county of New York, and State of New York, have invented certain new and useful Improvements in Apparatus for Generating Ozone, of which the following is a specification.

10 My invention relates to that class of apparatus in which an interrupted electric current of high tension and frequency is caused to pass between electrodes and through interposed dielectrics so as to produce a non-arcing, soft, ultra-violet glow or effluvia, the so-called silent electric discharge. When oxygen, air, or other gases are passed through the free space between such electrodes the electrical stress or bombardment 15 so greatly augments the vibration or movement of the atoms within the gaseous molecules that many of the atoms escape from molecular combination and reunite to form molecules of a different nature. This phenomenon is most frequently taken advantage of for the conversion of oxygen into ozone, but other gases may be altered in a similar manner.

It is well known that electrical discharges 20 take place most readily from points and least readily from smooth surfaces. Electrodes with perfectly smooth, plane surfaces are undesirable for this reason because the electric tension accumulates on such surfaces 25 until the electric strain ruptures at some point which may be nearest to the opposing electrode and an arc or violent discharge occurs. A multiplicity of points on the surfaces of the electrodes causes a more evenly 30 distributed discharge, but if any one of the points should extend farther toward the opposing electrode than the others, there will be a freer discharge from such point and a tendency to form an arc. Partly to 35 neutralize this tendency, di-electric plates, usually of glass, are customarily interposed between such electrodes to spread or diffuse the current by their resistance and thus to diminish the tendency to form arcs. The 40 usual method of forming such an element is to attach a sheet of metallic foil by means of an adhesive, such as glue, to the outer surface of a glass plate or tube. This has the disadvantage of forming a smooth elec-

trode surface and it has been sought to overcome this by first mechanically indenting or corrugating the metallic foil. Such mechanical indentations are, however, exceedingly coarse when compared with the fine soft non-arcing electrical discharge desired 50 and tend to cause arcing for this reason. It is also desirable that the dielectric be in intimate contact with the electrode surface at every point as, if it were not, there would be some points of closer contact and less resistance, from which the freer discharge of current would cause a local heating of the dielectric and cause an arc that would puncture the glass. In converting the oxygen of common air into ozone it is highly undesirable that any arcing occur, even incipient arcing, as such concentrated localized discharges cause the formation of nitrogen 55 oxids.

The object of my invention is, primarily, 60 to form what may be designated as a high-tension electrode element, consisting of a liquid electrode and a corresponding solid dielectric, whose opposing surfaces are at all points in substantially intimate contact, 65 and in which, such surfaces in contact, consist of an exceedingly great number of fine, uniform indentations and corresponding points, all of which lie practically in a true 70 plane. To attain this result I make use of 75 a glass plate or tube one of whose surfaces has been slightly but sensibly roughened by the action of hydrofluoric acid, the vapor or liquid, or by the action of a fine sand blast. Against this finely indented glass surface I 80 place a layer of metallic mercury or liquid conductive material, or other material which will enter the indentations and conform to the indented surface as an electrode. The 85 mobile conducting liquid enters the fine indentations in the surface of the glass and thus forms an electric discharging surface 90 with an innumerable number of fine points of discharge, and at the same time the electrode surface and the dielectric surface are 95 100 in absolutely uniform intimate contact.

Another object of my invention is to so combine these high tension, electrode elements in couples or pairs with suitable air spaces between the opposed dielectric surfaces as to form a complete unit for producing a soft, high-tension, electric discharge 105 between such electrodes when connection is

made to the electrodes from a source of high-tension interrupted electric energy.

A further object is an improved mechanical construction whereby the apparatus is 5 readily assembled, or taken apart, rigid joints and cements are avoided, and simplicity of construction is attained.

The nature of the invention and the method of construction are fully shown in 10 the drawings, of which—

Figure 1 shows a completely assembled unit or apparatus of one style of construction; Fig. 2 is a vertical section of a modified form of the same; Fig. 3 is a broken 15 vertical section of an electrode element, with an exaggerated detail of the indentations in the dielectric and a section of the removable cap which seals the tube; Fig. 4 is a detail which shows a further method of joining 20 and sealing the bottom edges of two concentric glass tubes of an outer electrode element; Fig. 5 is a shortened vertical section of a preferable form of an apparatus or unit with a modified sealing device or cap; Fig. 25 6 is a vertical section showing two complete electrode elements, assembled with base and sealing cap to form a completely assembled apparatus; Fig. 7 is a horizontal cross-section of Fig. 6 on the lines VII—VII; Fig. 30 8 is a horizontal cross-section of Fig. 6 on the line VIII—VIII, and Fig. 9 is a plan view of the base.

Throughout the drawings the same numbers are used in the main to designate similar parts.

Referring to the outer electrode element, shown in Figs. 1 and 3, it will be seen that two tubes, preferably of glass, are employed which are preferably so proportioned and 40 positioned with respect to each other that there is an annular uniform concentric space 1 between the walls of the tubes. In Fig. 3 both tubes are closed at the bottom in a concentric, hemispherical form and the space 45 between the tubes at the bottom is filled with a dielectric cement or lute 2, such as is produced by melting shellac or gilsonite, and this dielectric filling or cement 2 extends to a horizontal line 3 in the cylindrical portion 50 of the space. The inner tube 4 serves the purpose of a dielectric and may be of a suitable thickness, preferably $\frac{3}{2}$ of an inch. Its outer surface, that is, its surface of greatest diameter, from a point at a line 3 to 55 a line 5 near the top of the tube, is previously roughened by submitting the surface to the action of hydrofluoric acid in some form, or to the action of a fine sand blast. The outer tube 6 is expanded near the top 60 into a cylindrical form of greater diameter than the main column of the tube. This forms a wide annular space or cup 6' open at the top. The annular cylindrical space 1, including a portion of the expanded annular space 8 formed by 6', is filled, from the

top of the dielectric filling 2 from line 3 to the line 5 at the top of the electrode element, with mercury or other conducting substance. This approximately includes all that portion of the inner dielectric tube 4 which has been 70 roughened. The open top of the cylindrical electrode element, above described, is closed by a cap 7, the main body of which is shown, with suitable outlet and inlet connections; and this cap is made of any non-conducting, 75 ozone-resisting material and its cylindrical portion is of a diameter which will allow it to enter the annular space at the top of the electrode element. This annular cup is designated by 8, and the vertical cylindrical body of the cap by 9, and the height of the sides of the cap 7 is such that its lower edge rests upon the shoulder 10 at the bottom of the annular cup 8, and the cap 7 is held approximately in a position concentric with the dielectric tube 4 by points or teats 11 placed at intervals around the lower edge of the cap. The mercury or other conducting substance in the annular space 1 extends up into the annular cup 6' to the line 5 and thus 80 envelops the body 9 of the cap 7, and hermetically closes the main body of the electrode element from the atmosphere. This cap 7 and the cup 6', with the mercury or other fluid electrode, thus form a liquid seal hermetically tight but readily broken by raising the cap vertically from position and thus giving immediate and easy access to the interior. Electrical connection from a 85 source of high-tension, interrupted electrical energy is made to the mercury electrode by means of a metallic wire or flat metallic strip 12; which strip is thrust into the mercury through the annular space between the walls 9 of the sealing cap 7 and the outer wall 6' of the annular cup. This electrode element has been described in detail because 90 it constitutes one of the main features of the invention. The ideal surface from which to secure a soft, uniform, non-arcing, high-tension electrical discharge is one containing an innumerable number of very fine points, all 95 of which points lie in a plane. If any one of the points extends appreciably beyond this surface, beyond the other points, it establishes a point of free or violent discharge and the main discharge will take this path 100 and form an arc. In the glass dielectric tube 4, I start with a smooth cylindrical plane surface, which, when roughened, contains an innumerable number of fine indentations. The roughening need be only slight but should be uniform. The mercury 105 or other conducting material which is highly mobile when poured into the annular, cylindrical space 1 takes the form of the indented surface 13 and forms an electrode with a discharging surface consisting of an innumerable number of fine points, all of which lie 110 in a plane, flat or cylindrical, with respect 115 to the axis of the electrode element. The 120 mercury or other conducting material is highly mobile when poured into the annular, cylindrical space 1 takes the form of the indented surface 13 and forms an electrode with a discharging surface consisting of an innumerable number of fine points, all of which lie 125 in a plane, flat or cylindrical, with respect 130 to the axis of the electrode element.

to each other. The opposing surfaces of the electrode and the dielectric are in intimate contact at every point. This intimate contact at every point between the surfaces of the electrode and the dielectric, so as to provide the electrode with a plurality of fine discharge points, has never, to the knowledge of the inventor, been employed before and is of great importance, as the finely pointed surface, maintains a uniform electric tension at all parts of the electrode.

In Fig. 5 an inner electrode element of similar construction is shown. In this case the outer tube 4^a of the two concentric tubes becomes the dielectric tube and is etched on its inner surface, or surface of smallest diameter 13. The inner or smaller tube 6^a is contracted concentrically at the top so as to form an enlarged, concentric, cylindrical cup 6^a, which acts, with the fluid electrode, as a liquid seal, in the same manner as already described for the outer electrode tube, at 6'. A cylindrically shaped cap, which will be described below, is inserted into this space 8^a and the electrode material is brought up to a point which incloses the lower edge of the cap 7^b, thus hermetically closing the interior of the inner electrode element.

Fig. 5 shows a highly desirable method of construction and assembling of the inner and outer electrode elements, of their top sealing caps and also of the electrical connections. In regard to the electrical connections, it will be noted that the wire or strip connection into the outer electrode is separated from the dielectric wall 4^a by the side wall 9 of the cap 7, and does not at all come into contact with the roughened surface of the dielectric wall 4. Likewise it will be seen that the inner wire connection 26^b to the mercury electrode, enters an aperture in the neck 25' and passes downward within this glass neck, and enters the electrode liquid in the cup 8^a behind the wall 9^a of the cap 7^b and is thus separated from contact with the roughened wall of the dielectric tube. The two high-tension wire connections are thus separated from each other by the glass walls of the caps and the pointed ends of the wire connections are kept from contact with the dielectric walls. The danger of a free discharging point being formed by the end of the wire or other connector is thus avoided. The outer electrode element and its sealing cap is similar to the form shown in Fig. 3, excepting for the method of joining the lower edges of the two concentric tubes, and the method of roughening. In Fig. 3 the two concentric glass tubes are both closed at the bottom ends and then, after inserting the dielectric tube into the outer tube, the space at the bottom between the tubes up to the lower line of the electrode material is filled with a non-conducting cement or lute 2, for

the purpose of holding the tubes in relative position and to limit the lower edge of the electrode. In Fig. 5 the two concentric glass tubes of the electrode element are joined at the lower edge 14' at the point or line corresponding to line 3 in Fig. 3 by fusing the glass edges and uniting them in a solid glass joint. The dielectric tube and the corresponding or complementary tube constituting the dielectric portion of the electrode element thus become one integral part. Instead of previously roughening the surface of the electrode tube before assembling, it is preferably roughened by filling the annular space 1^a with a suitable etching acid until the proper roughening or frosting is produced. This method of forming a solid union at the bottom between the two tubes of an electrode element is shown also at 14 in Fig. 5, and at 15 and 15' in Fig. 6.

In Fig. 4 another form of the method of joining the lower ends of the tubes of the outer electrode element is shown. The bottom end of the inner tube, or dielectric tube 16, is closed in hemispherical form, but the outer inclosing tube 17 ends in open cylindrical form at the lower line of the mercury electrode. The tubes are then spaced and joined hermetically by a cap 18 of hard rubber, fiber or other non-conducting material, which serves to hold the tubes in concentric relation. This cap follows the contour of the tubes, forming a shoulder at the bottom edge of the outer tube with a vertically projecting ring portion around the edge of the tube, and is held in permanent position by a rubber, water-glass, or other adhesive material. In Fig. 2 an outer electrode element is shown whose tubes 19 and 20 end in straight cylindrical open form and are sealed or joined by being embedded in a non-conducting matrix or bed 44, such as may be produced by melting shellac or gilsonite, which enters the space between the tubes and closes said space. A conductor 44^a extends into the body of electrolyte between the tubes 19, 20, through the bed 44 and the material sealing the space between the bottom of the tubes, said conductor entering the jar 32 through a plug 44^b in an opening in the jar, and being incased in an insulating jacket of glass 44^c.

The cap 7 or sealing top for the outer electrode element has been partially described in reference to Fig. 3. A full vertical section of this cap is shown in Fig. 1. It consists of the already described main part or cylindrical body 9 of such a diameter and depth as to enter the liquid seal cup 8 or annular space in the top of the electrode element, and to rest on the shoulder 10 of the latter. This cap is closed by a dome-shaped top, at the center of which is a vertical tubular extension or opening 21. At one side of the center is another opening 130

to which is permanently attached, preferably as an integral part of the cap, a curved tube 22 which is bent into a semi-circle so that its outer end 23 is perpendicular to the horizontal. This end 23 is expanded to a greater diameter than that of the main part of the tube so as to enter the annular space of a small liquid seal cup 24. This small sealing cup 24 is shown in Fig. 1 as being attached to a receiving vessel. Its construction is that usually employed for similar purposes in chemical or physical apparatus. In Fig. 6 this small liquid seal 24 is shown in connection with a pipe distributing device 25^a. This cap, by virtue of the fact that the lower edge of the cap itself and the pipe connection 22 therefrom enter liquid seal cups freely in a vertical and parallel direction, can be easily removed at any time from position. The central tubulure or neck 21 is of somewhat larger internal diameter than the neck 25 extending from the inner electrode element and passes freely over such neck or tube 25. The small annular space between such neck 25 and the tubulure 21 is closed to the atmosphere by a washer 26 of suitable material, such as cork, felt, fiber, or asbestos cord. This washer 26 is held in place, and the cap 7 is firmly attached to the neck 25 by means of the split metallic ring or clamp 27 surrounding the tubulure, and which also serves as a binding clamp for the electrical conductor leading to the inner electrode element. This cap 35 may be practically the same in every form of the apparatus illustrated, and is thus shown in Figs. 1, 2, 3, 4 and 6.

In Fig. 5 a second, inner cap 7^b for the inner electrode element is shown. This cap, like the large outer cap, consists of an enlarged cylindrical portion 9^a which dips into the annular electrode space 8^a of the inner electrode element and thus hermetically seals the upper end of the inner tubular part of the electrode element. This vertical cylindrical portion 9^a is contracted into a central, smaller, vertical, tubular portion or neck 25' which extends upward through the neck 21' on the larger outer cap 7^a, and is sealed thereto and firmly held by the washer 26', and clamp 27'. Electrical connection is made to the inner mercury electrode by passing a wire through a small orifice 26^b in neck 25', and said wire extending downward through the interior of the neck into electrical connection with the electrode element. The outer end of this wire is clamped in place on the neck 25' by the split clamp 27'. When it is desired to gain access to the interior of the electrode elements, the two caps 7^a and 7^b, firmly joined together by the neck tubes 21' and 25' and by the washer 26 and clamp 27', by virtue of their vertical position in parallel in the large mercury seals 8 and 8^a, and in the

small seal 24, shown in Fig. 1, can be lifted readily out of position.

Three forms of inner electrode elements are shown in the drawings and that in Fig. 5 has already been described. In Fig. 6 the inner electrode element consists of double concentric glass tubes, as in Fig. 5, but instead of ending at the top in an annular space for use as a liquid seal the inner of the two tubes is drawn out into a small tube or neck 25 which passes upward through the neck or tubulure 21 of the cap 7, and is firmly united therewith by the washers 26, 26' and the split metallic clamp 27.

Another form of inner electrode element is shown in Figs. 1 and 2, and in broken section in Fig. 4. This consists of a straight cylindrical glass tube 28 contracted at the top into a small tubular neck 25 which neck enters the neck or tubulure 21 of the cap 7 and is attached thereto by washers 26, and clamp 27. This tube 28 is lined on its inner surface with a metallic foil 29 attached thereto by means of an adhesive, such as glue, water-glass, or egg albumen. This form of construction is made possible because I have found that the use of one roughened liquid electrode element is practically sufficient with its uniform finely pointed plane surface, to prevent arcing, and therefore, only the surface of the wall 4 away from the air or gas space need be roughened, as clearly shown in Fig. 4. This form of construction is not so desirable as that in which the mercury electrode elements are used in pairs, but is cheaper to construct, although not so safe and reliable in use.

The method of making electrical connection to the mercury electrodes has already been described, but in the case of the inner electrode elements 28 contact is had by means of a wire 30 introduced through an aperture in the neck of the inner tube and ending within the tube in a ball or spherical basket of wire 31, whose sides are in spring contact with the metallic foil 29 on the inner wall of the tube 28. In Fig. 2 this wire 30 is shown entering through the shellac or other non-conducting seal or matrix 44 at the bottom of the tube.

In Figs. 1 and 2 is shown an outer heavy glass cylinder 32 which serves for support and protection of the electrode elements and is also designed to be used in connection with a current of air for cooling the ozone tubes proper. For this purpose the cylinder 32 has an opening or tubulure 33 at its base and openings or vents 34 near its top. Air from any convenient source is caused to enter at 33 and, passing around the electrode elements, it tends to carry off any heat that may be generated by the electrical resistance in the tubes and passes through the outlets 34.

The preferable method of supporting the electrode elements is shown in Fig. 6 in which 35 is a cylindrical, hollow base or support of any suitable, non-conducting material, such as insulating fiber, porcelain or glass. A plan view is shown in Fig. 9. The lower, inner cylindrical portion of this base is of a slightly larger diameter than the inner electrode element, which it is intended to receive. As it is not possible to obtain blown glass parts of exact dimensions, washers 36 of cork, fiber, or other suitable material are inserted within this space for the purpose of adjusting the height of the inner electrode element and to serve as a support for it. Immediately under the electrode element is placed a special disk 37 which is radially slotted on the outer periphery so as to provide openings 38 under the edge of the inner electrode element or tube. In addition to this slotted disk 37 the walls of the cylindrical space are grooved vertically so as to provide air passages 39. The upper inner portion of the base is also of cylindrical, hollow form of a diameter slightly larger than that of the outer electrode element. On account of this opening being of larger diameter than the lower space, a shoulder or ledge 40 is formed which serves to receive the lower end of the outer electrode element and to support it. To adjust this outer tube to height, washers 41 are inserted under the tube resting upon the ledge 40. On account of the fact that the cylindrical openings in the base are concentric it will be seen that they serve to center the electrode elements so that the annular ozonizing space 42 will be of uniform thickness.

In Fig. 6 is shown a complete unit or ozonizing set the parts of which have been already described. It consists of an inner and an outer electrode element, each of which consists of two concentric glass tubes sealed by fusion at their lower ends so as to close the annular space. The interior space or walls of these double glass tubes is roughened by an acid etching so that when the annular cylindrical spaces in the electrode elements are filled with mercury or other conducting material the opposing electrode surfaces will assume the shape of the roughened glass surfaces with which the electrode material is in contact. The inner electrode tube is concentrically inserted within the outer larger electrode tube and the tubes are held in this concentric position by the centering action of the base 35 and the cap 7. It will be noted that the lower edge 15 of the inner electrode element extends below the lower edge 15' of the outer electrode element; also that the lengths of the two tubes or electrode elements are such that when properly adjusted the top edge of the electrode material in the inner electrode tube is higher than the top edge of the electrode in

the outer electrode tube. Although I have removed all danger of sharp concentrated discharges by the use of the finely pointed electrode surfaces and by the fact that the upper and lower edges in the case of mercury are naturally of rounded meniscus, this placing of the edges of the electrodes, not in opposition to the edge of the other electrode, but opposite to the plane surface, insures a softer discharge than if the discharge was from edge to opposite edge.

The inner and outer electrode tubes are supported by the base 35 and are adjustable as to absolute and relative height by the washers 36 and 41. A conducting liquid having been filled into the electrode spaces to a sufficient height to engage the edges of the cap 7 or caps 7^a and 7^b, in Fig. 5, and mercury, oil or water having been placed in the small mercury or liquid seal 24, the apparatus is sealed from the atmosphere by means of the caps with their connections. The washers 41 are preferably made of some soft material, such as cork, so that, when the bottom edge of the outer electrode element rests upon it, the washer will accommodate itself to any irregularities in the glass and thus make a tight joint. This object is furthered by the fact that when mercury is used as an electrode it is heavy and exerts considerable downward pressure. Electrical connection having been made by wires 12 and 12^a, dipping into the liquid electrodes of the inner and outer electrode elements respectively and by cutting such wires into circuit with a source of high-tension, interrupted electrical energy, air or oxygen, in case it is desired to generate ozone, are admitted to the inner tube 25 under pressure. The gas passes down and through the tubular interior of the inner electrode element and passes under its lower edge through the openings 38 in the disk 37, thence upward through the vertical grooves 39 in the walls of the base 35 to the annular ozonizing space 42. In this annular cylindrical space, which is preferably about $\frac{3}{16}$ of an inch wide, there is produced a silent electrical discharge which is manifested by its "ultra-violet" color. Unlike the discharge in other ozonizing apparatus, this high tension discharge or effluvia is so finely and uniformly diffused that no trace whatever of disruptive or "stringy" discharge can be detected. The ozone efficiency is extremely high for this reason and for the reason that the apparatus, when run continuously for long periods, reaches a maximum temperature that is only slightly apparent to the touch. This is a very important advantage as it not only increases the ozone production but also indicates a high electrical efficiency. The air or gas after passing upward through the ozonizing space 42 escapes into the space 43 under the dome of the cap 7, and thence, by

means of the curved pipe 22, passes through the liquid seal connection 24 to a receiving vessel or to a system of distributing pipes 25^a.

- 5 The apparatus as shown fully in Fig. 6 and the separate electrode elements, as shown in Figs. 3 and 5, if used entirely without the roughening of the dielectric surface, will serve for the purpose specified and 10 forms a modified form which it is unnecessary to illustrate in the drawings, as this modified form is the same in every other respect as that shown excepting in the omission of the roughening. This style is not, 15 however, the preferable form.

The inventor does not limit himself to the exact construction shown, as other forms than cylindrical tubes may be desirable, as, for example, flat etched glass trays filled 20 with a liquid electrode in contact with the glass surface and a series of such trays arranged or assembled horizontally in pairs and connected alternately with the positive and negative sides of a high-tension electrical source of energy, or flattened box-shaped 25 glass vessels etched on the interior surfaces and filled with mercury or other conducting liquid may constitute the electrode elements and such electrode elements be arranged in 30 vertical parallel position. Likewise, in Figs. 1, 2 and 4, are shown etched fluid-electrode outer elements with inner electrode elements of a single glass tube coated with a metallic foil. This arrangement is equally effective 35 if the foil-coated electrode element is used as the outer one and the etched fluid-electrode element is employed as the inner one, and this arrangement is employed by the inventor.

- 40 In the drawings the inlet and outlet for the air or gas and the ozonized product are shown only at the top. It is sometimes preferable to put both openings at the bottom within the base and the top caps then become 45 merely plain sealing caps. It is also sometimes convenient to place one opening at the top, and one at the bottom with suitable arrangement for distributing the air or gas. The preferable arrangement is 50 shown in the drawings but these alternate methods are within the scope of the invention.

If mercury is used as the electrode material, it is not necessary to have it extend 55 entirely to the top in the sealing cup but a paraffin oil or glycerin or other non-conducting, difficultly oxidizable fluid may be employed to form the sealing fluid, as shown at 45 in Fig. 1.

- 60 While I have described the electrode part as consisting of mercury or other conducting liquid, it may consist of an easily fusible metal cast in contact with the finely indented surface of the dielectric, or of an

amalgam composition. In the use of a conducting liquid as the electrode other than mercury I preferably employ water acidulated with sulfuric acid.

What I claim and desire to secure by Letters Patent of the United States is:—

70 1. An electrode element consisting of two concentrically positioned glass tubes separated by an annular space closed at one end, one of which tubes is roughened on the inner surface, and a liquid electrode contained within the annular space, and in contact with the roughened surface.

75 2. An electrode element consisting of an annular double walled cylindrical glass vessel, and a liquid conductor within the annular spacing, one of said walls constituting a dielectric part and the liquid conductor the electrode part.

80 3. An electrode element consisting of an annular double walled cylindrical glass vessel, and a body of mercury within the annular spacing, one of said walls constituting the dielectric part and the mercury the electrode part.

85 4. An electrode element consisting of a roughened dielectric plate, a parallel inclosing part and an inclosed fluid electrode part in contact with the roughened surface of the dielectric, said electrode part entering the indentations of said roughened surface to provide said electrode with a plurality of fine discharge points.

90 5. A fluid electrode containing vessel consisting of two concentrically positioned glass cylinders separated by an annular space closed at one end and having one of the inner annular surfaces roughened.

95 6. An annular, cylindrical, fluid-electrode containing vessel, permanently closed at one end, made of dielectric material, and having its inner annular surfaces roughened by acid etching or its equivalent.

100 7. An electrode element comprising concentric dielectric shells spaced from each other, one of the same having a roughened surface, and a body of mercury inclosed in the space between the said shells and entering the roughened surface whereby the mercury is provided with a plurality of fine discharge points.

105 110 8. An electrode element comprising concentric cylindrical dielectric shells separated by an annular space, the inner surface of one of the dielectrics being roughened, and a body of liquid conductive material confined within the said annular space and entering the indentations of the roughened surface whereby said material is provided with a plurality of fine discharge points.

115 120 9. An electrode element comprising concentric hollow dielectrics spaced from each other, a liquid conductive material confined in said space, the surface of one of the di-

electrics defining said space being roughened, whereby the said material is provided with a plurality of fine discharge points.

10. In an ozonizing apparatus, electrodes spaced from each other to provide an air gap, one of said electrodes comprising a dielectric having its surface away from the air gap roughened to provide finely divided indentations, and a conducting body applied to said roughened surface and entering said indentations to form a discharge surface containing a plurality of fine points directed toward said air gap.

11. In an ozonizing apparatus, electrodes spaced from each other to provide an air gap, one of said electrodes having a surface toward the air gap roughened to provide finely divided indentations, and a fluid conducting body applied to said roughened surface and entering said indentations to form a discharge surface containing a plurality of fine points directed toward said air gap.

12. In an ozonizing apparatus, electrodes spaced apart from each other in parallel relation to provide an air gap, one of said electrodes having a surface toward the air gap roughened to provide finely divided indentations, and a fluid conducting body applied to said roughened surface and entering said indentations to form a discharge surface containing a plurality of fine points directed toward said air gap.

13. An ozonizing apparatus comprising concentric cylindrical dielectrics spaced by an annular space, the inner surface of the inner dielectric being roughened, and a body of liquid conducting material applied to said roughened surface and entering the indentations thereof, whereby the said material is provided with a plurality of fine discharge points directed toward the said annular space.

14. An ozonizing apparatus comprising inner and outer hollow electrodes spaced from each other, one of said electrodes consisting of a double walled dielectric vessel having one of its inner surfaces roughened, a liquid conducting material in the space between said walls, and means for permitting air or gas to flow through the space between the electrode elements.

15. An annular cylindrical vessel of a dielectric material for containing a fluid electrode, the annular walls of which are closed at the bottom, and one of the inclosed surfaces being roughened.

16. In an ozonizing apparatus, tubular electrodes arranged one within the other and spaced from each other to form an air gap, one of said electrodes comprising a dielectric having its surface away from the air gap roughened to provide fine indentations, and a conducting body applied to said roughened surface and entering said indentations to

form a discharge surface containing a plurality of fine points.

17. In an ozonizing apparatus, tubular concentric electrodes arranged one within the other and spaced from each other to form an air gap, one of said electrodes comprising a dielectric having its surface away from the air gap roughened to provide fine indentations, and a conducting body applied to said roughened surface and entering said indentations to form a discharge surface containing a plurality of fine points.

18. An ozonizing apparatus comprising inner and outer hollow concentric electrodes spaced from each other, and means for causing a current of air or gas to pass through the hollow inner electrode and the space between said electrodes, said means consisting of a base having passages connecting the interior of the inner electrode with said space.

19. An ozonizing apparatus comprising inner and outer hollow concentric electrode elements spaced from each other, one of said electrode elements consisting of a double walled dielectric having one of its interior surfaces roughened, a liquid conductive material in the space between said walls, and means for causing a circulation of air or gas through said inner electrode and the space between it and the outer electrode.

20. An ozonizing apparatus comprising inner and outer hollow concentric electrode elements spaced from each other, one of said electrode elements consisting of a double walled dielectric having one of its interior surfaces roughened, a liquid conductive material in the space between said walls, means for admitting air or gas to the interior of the inner electrode, means for causing it to flow through the space between the electrode elements and an outlet.

21. An ozonizing apparatus comprising inner and outer hollow concentric electrode elements spaced from each other, one of said electrode elements consisting of a double walled dielectric having one of its interior surfaces roughened, a liquid conductive material in the space between said walls, an inlet to the interior of the inner electrode element, and an outlet from said space between the electrode elements.

22. An annular, cylindrical electrode vessel of a dielectric material for containing a fluid electrode, the annular walls of which are closed at the bottom by autogenous fusion and are roughened upon the annular inclosed surfaces.

23. An annular, cylindrical, fluid-electrode containing vessel, closed at the bottom, with concentric opposing walls, roughened as to one of their inner surfaces, and one of whose walls is expanded in a concentric cylindrical manner at the top to form an annular cup.

24. A cylindrical liquid electrode element, consisting of two concentric, dielectric walls, one of which walls is roughened on its inner surface, and one of which walls is expanded at the top into an annular cup, a liquid electrode within the annular space and extending into the annular cup and a non-conducting cap or cover dipping into the liquid in the cup.
25. A cylindrical, double walled, dielectric vessel of annular shape, closed at the lower annular opening, and one of whose walls is concentrically expanded at the upper end into an annular cup, one of said walls being roughened on its inner surface, a liquid electrode within the roughened annular space and extending into the annular cup, a dome-shaped cap positioned within the annular cup and dipping into the liquid therein to form a liquid seal, said cap having a central tubular opening and an eccentric tubular opening.
26. An ozonizing electrode element with annular walls, one of which is roughened on its inner surface, an annular liquid sealing cup, a liquid electrode in contact with the roughened walls and extending into the annular cup, and a dome-shaped sealing cap, having a central tubulated opening and an eccentrically attached curved pipe connection ending in an expanded end portion, the cylindrical walls of the cap and of the expanded end portion being parallel and extending downwardly in a direction perpendicular to the horizontal.
27. An ozonizing electrode element with annular dielectric walls, one of which is roughened on its inner surface, an annular liquid-seal cup, a fluid electrode in contact with the roughened wall and extending into the liquid-seal cup, and a dome-shaped sealing cap, having one central tubulated opening and an eccentrically attached curved pipe connection ending in an expanded end portion, and the cylindrical walls of the cap and of the expanded end portion being parallel and extending downwardly in a direction perpendicular to the horizontal, and a separate, annular-shaped, liquid-seal cup into the annular space of which, filled with liquid, the expanded end of the curved pipe dips, and makes hermetic union with a distributing or collecting apparatus.
28. In combination, an ozonizing element, consisting of an annular cylindrical dielectric vessel, one of the walls of which is roughened on its inner surface, and one of whose walls at the top is expanded concentrically to form an annular liquid-seal cup, a fluid electrode part within the annular space, and a fluid sealing part within the annular cup, a tubulated dome-shaped sealing cap of a non-conducting material positioned within the sealing cup and a metallic electrical conductor inserted into the elec-
- trode part between the outer wall of the sealing cup and the wall of the sealing cap and separated from the dielectric discharging wall by the wall of said cap.
29. An ozonizing electrode containing 70 vessel consisting of concentric, cylindrical dielectric walls, the inner surface of one of the walls of which is roughened, and which walls are closed or sealed with respect to the lower annular opening, and having the 75 inner or smaller tubular wall contracted at its top portion into a central, vertically extending tube of smaller diameter.
30. An electrode element for an ozonizing apparatus consisting of an annular, cylindrical double walled dielectric vessel, one of the walls of which is roughened as to its inner surface, and having a contracted tubular vertical extension of the walls of the smaller inner tube, a fluid electrode part within the 85 walls of the annular space and in intimate contact with the roughened surface, and a solid metallic electric conducting part held in position on the contracted tubular part of the dielectric tube by means of a binding 90 clamp and extending into the liquid electrode.
31. An inner electrode containing vessel consisting of cylindrical concentric dielectric walls one of which is roughened as to 95 its inner surface, closed as to the annular opening at one end, and expanded into an annular, cup-shaped part at the other end by a cylindrical, concentric contraction of the inner wall.
32. An ozonizing electrode element consisting of an annular cylindrical dielectric vessel roughened as to the inner surface of one of its walls, expanded at its top by a concentric, cylindrical contraction of its wall of 105 smaller diameter into a cup-shaped annular part and a liquid electrode part within the annular space and in intimate contact with the roughened dielectric wall.
33. In combination, an inner liquid-electrode element, consisting of an annular, double-walled, cylindrical, dielectric vessel, roughened as to one of its inner surfaces, closed at the bottom end as to its annular space, with an expansion at the top end of 110 its annular space into an annular, cup-shaped part, a dome-shaped sealing cap having a central contracted tubular opening and fitting freely into the annular cup-shaped part, a liquid-electrode part contained within the annular space and in intimate contact with the roughened dielectric wall and extending into the annular cup-shaped part and inclosing the lower edge of the sealing cap, and a metallic conducting 115 part, attached to the contracted tubular part of the sealing cap, passing within the tubular part and extending downwardly within the tubulated cap and making electrical contact with the liquid electrode part at a 120
- 125
- 130

point separated from the discharging dielectric wall by the vertical wall of the sealing cap.

34. An ozonizing electrode element consisting of a dielectric cylindrical part with a central contracted tubular extension, an electrode part consisting of a conducting body applied to one of the surfaces of the main cylindrical part, in combination with a roughened liquid-electrode containing element positioned concentrically with regard to first named electrode element on the side opposite the latter's dielectric part.

35. In combination with the inner and outer annular, cylindrical, liquid-electrode elements a base of non-conducting material in the form of a vertical cup, having an interior bore of vertical cylindrical shape of two diameters, the lower portion being of a diameter greater than the outer diameter of the inner electrode element and the upper portion of a diameter greater than the outer diameter of the outer electrode element, the cylindrical portions having a common vertical axis, the concentric walls serving to position the electrode elements in concentric relation, grooves in the inner wall of the smaller cylindrical portion, disks of non-conducting material within the smaller cylindrical portion and a disk of non-conducting material slotted at its periphery placed between the spacing disks and under the edge of the inner electrode element, and ring washers of non-conducting material positioned under the bottom edge of the outer electrode element serving to adjust it vertically and to seal the inner chamber of the electrode elements from the atmosphere.

36. An ozonizing apparatus or unit consisting of an outer annular-shaped, double-walled dielectric vessel, roughened on its inner surfaces, and expanded at its top into an annular cup, a dome-shaped cap with side walls positioned within the annular cup and with a vertical tubulure and an eccentrically placed curved tubular outlet which ends in an expanded portion extending downward into an annular cup forming a seal device, a seal cup joining the curved tubular opening to a receiving device, a liquid-electrode part in the roughened annular space in the dielectric part and extending into said annular cup of said part to seal the edge of the dome-shaped cap, a metallic connecting part from a source of electrical energy extending into the liquid-electrode part between the outer wall of the annular dielectric cup and the wall of the tubulated sealing cap, an inner annular-shaped, double-walled dielectric vessel positioned concentrically with regard to the outer electrode element and roughened as to one of its inner surfaces, and contracted and extended vertically upward with respect to its inner wall into a tubular part

extending through the central tubulure of the sealing cap of the outer, dielectric element, means for hermetically sealing the opening between the neck of the inner dielectric part and the tubulure of the sealing cap of the outer dielectric part, a binding clamp uniting the cap to said neck, and a metallic conducting part connecting the binding clamp with the inner electrode element, and an inner liquid electrode part filling the annular, roughened dielectric part and in intimate contact with its roughened wall, and a non-conducting base centering the electrode elements in the form of a cylindrical cup, the lower portion of the base having a diameter greater than the outer diameter of the inner electrode element and the upper portion of the base having a diameter greater than the outer diameter of the outer electrode element, both cylindrical portions having a common vertical axis, grooves in the wall of the smaller cylindrical portion, spacing washers for adjusting the height of the inner electrode element, and a disk of non-conducting material under the bottom edge of the inner electrode element and having peripheral openings whereby a free passage is formed from the central tubular portion of the inner dielectric element under its edge to the vertical corrugations of the wall of the base and thence into the annular space between the inner and outer electrode elements, and ring washers of soft non-conducting material under the edge of the outer electrode element to adjust it as to height and to seal the inner space from the atmosphere.

37. An apparatus for producing ozone comprising inner and outer electrode elements, concentrically positioned, the outer electrode element consisting of an annular, cylindrical dielectric vessel, roughened as to one of its inner surfaces, expanded at its top into a liquid sealing part and having in its annular space a liquid electrode, an inner, electrode element, consisting of an annular, cylindrical dielectrical vessel, roughened as to its inner surfaces, and expanded as to its top into a sealing part and having in its annular space a liquid electrode part; a supporting and sealing base of a non-conducting material having a cylindrical interior portion of two diameters, the part of smaller diameter supporting the inner electrode element, and the part of greater diameter supporting the outer electrode element, grooved passages within the base from the inner tubular portion of the inner electrode element to the annular vertical space between the two electrode elements; a cap of non-conducting material with an upwardly-extending tubular opening and positioned in the annular sealing cup of the inner electrode element; a cap of non-conducting material positioned in the annular

sealing cup of the outer electrode element and having a tubulure engaging the tubular extension of the inner cap and being attached hermetically thereto and having a 5 second tubular opening to connection with an external liquid-seal cup; metallic conductors in electrical connection with the liquid-electrodes in the liquid seal parts of the electrode elements separated from the 10 discharging dielectric walls by the respective walls of the sealing caps.

38. An ozonizing apparatus comprising an annular, cylindrical dielectric vessel roughened as to one of its inner surfaces, and containing a liquid-electrode part and an electrical connection therewith, forming one electrode element, and a second concentrically positioned electrode element consisting of a cylindrical dielectric part and a conducting body applied to the dielectric part 20 and an electrical connection therewith, and means for closing and assembling such elec-

trode parts so that gas or air may be passed through the annular space between the electrode elements.

39. In an ozonizing apparatus, the combination of concentric electrode elements, and means for separating the same from each other and from the atmosphere, consisting of a liquid seal inclosing said elements.

40. In an ozonizing apparatus, the combination of concentric electrode elements, and means for separating the same from each other and from the atmosphere, consisting of concentric liquid seals inclosing said ele- 35

In testimony whereof I have hereunto signed my name in the presence of two subscribing witnesses.

WILLIAM JOHN KNOX.
